UNITED STATES PATENT OFFICE.

WALTER S. MURDOCK, OF HOUSTON, TEXAS.

ROTARY TOOTHBRUSH.

Application filed November 22, 1924. Serial No. 751,658.

This invention relates to new and useful improvements in a rotary tooth brush.

One object of the invention is to provide a rotary tooth brush embodying a holder, or handle, and a substantially cylindrical brush and also embodying a novel type of drive shaft whereby the brush may be manually rotated in either direction with respect to the handle.

Another object of the invention is to provide a rotary toothbrush embodying a handle having a drive shaft therein and a substantially cylindrical brush detachably connected to said drive shaft in a novel manner and also including a novel type of lip piece connected to the brush and forming a close fitting joint with the handle.

A further feature of the invention resides in the provision of a tooth brush so constructed as to exclude the entrance of water, moisture, or foreign matter from the inside of the handle.

A still further feature of the invention resides in the provision of a rotary tooth brush, composed of few parts so assembled that there will be little wear on the parts that are movable, and which may be cheaply constructed and easily assembled or taken apart for cleansing; and it is to be further noted that the brush proper may be readily detached, when worn out and replaced with a new one.

With the above and other objects in view this invention has particular relation to certain novel features of construction, operation and arrangement of parts an example of which is given in this specification, and illustrated in the accompanying drawings, wherein:—

Figure 1 shows a longitudinal sectional view of the device. Figure 2 shows a side view, of the rotary brush and brush shaft, with the attached lip piece shown in section.

Figure 3 shows an enlarged cross sectional view taken on the line 3—3 of Figure 1.

Figure 4 shows a fragmentary side view of the brush driving shaft.

Figure 5 shows an end view thereof.

Figures 6 and 7 show side and end views of a bearing ring employed.

Figure 8 shows a side view of the handle, and

Figure 9 shows a cross sectional view of the brush taken on the line 9—9 of Figure 1.

Referring now more particularly to the

drawings, wherein like numerals of reference designate similar parts in each of the figures, the numeral 1 designates the handle, which may be formed of celluloid or other suitable material. This handle has a lengthwise bore to receive a metallic tubular lining 2, which is suitably secured therein and one end of which is flush with the corresponding end of the handle and whose other end, as 3, projects beyond its corresponding end of the handle. This lining forms a bearing for the crank shaft and crank, hereinafter described, and its extended end 3 gives a longer bearing for the brush shaft, 70 hereinafter referred to, and prevents the wobbling of said brush shaft and said extended end also assists in excluding water and foreign matter from the inside of the handle.

There is a crank shaft 4 rotatable in the lining 3, one end of which has the crank 5 attached thereto. This crank is formed with an annular abutment, or bearing 6 which bears against the adjacent end of the lining 2, which thus protects the corresponding end of the handle 1 against wear, and the free end of the crank carries the usual rotatable grip member 7, of any desired form, by which the crank may be turned.

The other end of the crank shaft 4 has a deep socket 8 to receive the twisted-wire brush shaft 10, and this end of the crank shaft has opposed slots 11, 11, and a removable surrounding bearing ring 12. This ring rotates with the crank shaft, one end bearing against the adjacent end 3 of the lining 2, thus minimizing any wear on this end of the crank shaft and being easily and cheaply replaced when it is worn out; and the other, or outer, end of this ring has opposing end notches 13, 13 in which the outwardly extending lugs 14, 14, carried by the adjacent end of the crank shaft, fit. The slits 11 form this end of said crank shaft 100 into flexible prongs as shown in Figure 4, which are held against spreading by said bearing ring 12 and which may be pressed together to receive said ring and when released will seat the lugs 14 into the notches 13. The abutment 6 and the ring 12 thus hold the crank shaft 4 against endwise movement.

As clearly illustrated in Figure 5 the opposite ends of the lugs 14 are dressed down, thus slightly flattening this end of the crank shaft 4, so that when the prongs are pressed together the diameter of this end of the

crank shaft will be less than the diameter of the ring 12, and the lining 2, and said ring may then be readily removed and the crank shaft 4 withdrawn through said lining.

As before stated the brush shaft 4 is formed of twisted, non-corrosive wire and its inner end is designed to fit snugly into the deep socket 8 of the crank shaft. The outer end of this shaft 10 carries the bristles, of which the brush 15 is formed. These bristles are inserted between the wires before they are twisted together and are so distributed that the brush will be of uniform density from end to end. The butt end of the brush is preferably of cylindrical form for about one third of the length of the brush and then slightly tapers to the free end of said brush, as illustrated in Figures 1 and 2. This form of brush will conform more closely to the inside of the teeth than a straight line, or true cylindrical brush.

A portion of the shaft 10, adjacent the brush is flattened, said flattened portion extending into the slots 11 and, in effect, forming a clutch with the shaft 4 so that the brush will rotate with said shaft.

A lip piece 16 is fitted around the flattened portion of the shaft 10 adjacent the brush, and is cemented, or otherwise secured thereon so as to form a water tight joint. This lip piece is extended and enlarged, so as to space the enlarged portion from the shaft 10 thus forming, in effect, a cap-like bearing 17, which fits over the projecting end 3 of the lining 2 and abuts against the adjacent end of the handle 1 to form a comparatively tight joint to exclude water or foreign matter.

In use the brush 15 is inserted into the mouth and the lips closed around the lip-piece 16 and said brush is then rotated in either direction by hand. The mouth being closed the cleansing agent, and saliva will be retained in the mouth and at the same time the water tight joint between the lip-piece 16 and the shaft 10, as well as the projecting hood 17 will protect the inside of the handle against moisture and foreign matter. The teeth will thus be thoroughly cleansed and the adjacent parts of the mouth massaged.

The brush 15 will be the only part that will readily wear out and this part, together with the shaft 10 and lip-piece, may be readily removed and replaced when worn out.

What I claim is:—

1. An implement of the character described including a handle having a longitudinal bore, a metallic lining in the bore forming a bearing, a shaft in said bearing, means for rotating the shaft, a brush carried by and detachable from the shaft, said bearing being extended, at one end, beyond the

handle, a lip piece fixed to the brush and fitting over said extended end.

2. An implement of the character described including a handle, a shaft extending through, and rotatable in said handle, means carried by one end of the shaft to rotate the same, the other end of said shaft having a deep socket and a side slot, a ring around the slotted end of the shaft, a tubular extension carried by the handle around the slotted end of the shaft which bears against said ring, a brush shaft one end of which is fitted into said socket and is provided with a lateral extension which engages with said slot, a brush on the other end of said brush shaft.

3. An implement of the character described including a handle, a shaft extending through, and rotatable in said handle, means carried by one end of the shaft to rotate the same, the other end of said shaft having a deep socket and a side slot, a ring around the slotted end of the shaft, a tubular extension carried by the handle around the slotted end of the shaft which bears against said ring, a brush shaft one end of which is fitted into said socket and is provided with a lateral extension which engages with said slot, a brush on the other end of said brush shaft, and a lip piece secured around the brush shaft, one end of which is adjacent the brush and the other end of which fits around said ring and extension.

4. An implement of the character described including a handle, a shaft extending through, and rotatable in said handle, means carried by one end of the shaft to rotate the same, the other end of said shaft having a deep socket and a side slot, a ring around the slotted end of the shaft, a tubular extension carried by the handle around the slotted end of the shaft which bears against said ring, a brush shaft one end of which is fitted into said socket and is provided with a lateral extension which engages with said slot, a brush on the other end of said brush shaft, and a lip piece secured around the brush shaft, one end of which is adjacent the brush and the other end of which fits around said ring and extension, the end of said lip piece adjacent the brush and having water proof material between it and said shaft forming a water tight joint with the brush shaft.

5. An implement of the character described including a handle, a shaft extending through, and rotatable in said handle, means carried by one end of the shaft to rotate the same, the other end of said shaft having a deep socket and a side slot, a ring around the slotted end of the shaft, a tubular extension carried by the handle around the slotted end of the shaft which bears against said ring, a brush shaft one end of which is fitted into said socket and is provided with a lateral

extension which engages with said slot, a brush on the other end of said brush shaft, and a lip piece secured around the brush shaft, one end of which is adjacent the brush and the other end of which fits around said ring and extension, the end of said lip piece adjacent the brush being cemented to the brush shaft and thus forming a water tight joint with the brush shaft, and its 10 other end abutting against the adjacent end of the handle.

6. In a device of the character described having a handle and a drive shaft therein having end slots, a brush shaft, a brush carried by one end thereof, said brush shaft being flattened adjacent the brush, said flat portion being adapted to fit into said slots, a tubular lip piece secured on the brush shaft adjacent the brush, and whose end, remote from the brush, is spaced from the shaft, and thus forming a lip guard around said shaft.

7. In a device of the character described a brush shaft, a brush carried by one end thereof, a lip piece secured around said shaft whose end, remote from the brush, is spaced from the shaft, said lip piece being cemented to and forming a water tight joint with the shaft.

30 8. An implement of the character described including a handle, a drive shaft extending through said handle and rotatable therein, means carried by one end of the shaft for rotating the same, the other end of the shaft having a deep socket and side slots forming prongs, lateral lugs carried by the prongs, a bearing ring around said prongs formed with end notches wherein the lugs are adapted to seat, a brush, a brush shaft 35 on one end of which the brush is fixed, the other end of the brush shaft fitting into said socket.

9. An implement of the character described including a handle, a drive shaft extending through said handle and rotatable therein, means carried by one end of the shaft for rotating the same, the other end of the shaft having a deep socket and side slots forming prongs, lateral lugs carried by the prongs, a bearing ring around said prongs formed with bearings wherein the lugs are adapted to seat, a brush, a brush shaft 40 on one end of which the brush is fixed, the other end of the brush shaft fitting into said socket and having lateral extensions which fit into said slots.

55 10. An implement of the character described including a handle, a drive shaft extending through said handle and rotatable

therein, means carried by one end of the 60 shaft for rotating the same, the other end of the shaft having a deep socket and side slots forming prongs, lateral lugs carried by the prongs, a bearing ring around said prongs 65 formed with recesses wherein the lugs are adapted to seat, a brush, a brush shaft on one end of which the brush is fixed, the other end of the brush shaft fitting into said socket, a tubular extension carried by the handle and fitting around the slotted end of said drive 70 shaft and abutting against said ring.

11. An implement of the character described including a handle, a drive shaft extending through said handle and rotatable therein, means carried by one end of the 75 shaft for rotating the same, the other end of the shaft having a deep socket and side slots forming prongs, lateral lugs carried by the prongs, a bearing ring around said prongs 80 formed with end notches wherein the lugs are adapted to seat, a brush, a brush shaft fitting into said socket, a tubular extension carried by the handle and fitting around the slotted end of said drive shaft and abutting against said ring, and a tubular lip piece 85 around the brush shaft, one end of which is adjacent the brush and whose other end is fitted around said ring and extension.

12. An implement of the character described including a handle having a lengthwise bearing therethrough, a drive shaft fitted through said bearing, means carried by one end of said shaft for rotating the same, the other end of the shaft having a deep 90 socket and side slots forming flexible prongs, outwardly extending lugs carried by the prongs and forming means for retaining said shaft in its bearing, a brush shaft fitted into said socket and operatively connected with said drive shaft and a brush carried 95 by said brush shaft.

13. An implement of the character described including a handle having a lengthwise bearing therethrough, a drive shaft fitted through said bearing, means carried 100 by one end of said shaft for rotating the same, the other end of the shaft having a deep socket and side slots forming flexible prongs, a removable bearing ring around 105 said prongs, outwardly extending lugs carried by the prongs and forming means for retaining said ring thereon, a brush shaft fitted into said socket and operatively connected with said drive shaft and a brush carried 110 by said brush shaft.

115 In testimony whereof I have signed my name to this specification.

WALTER S. MURDOCK.
